UNITED STATES PATENT OFFICE.

JOHANN BROGER, OF BADEN, SWITZERLAND, ASSIGNOR TO AKTIENGESELLSCHAFT BROWN, BOVERI & COMPANY, OF BADEN, SWITZERLAND.

APPARATUS FOR COOLING METAL-VAPOR RECTIFIERS.

Application filed March 28, 1921, Serial No. 456,295, and in Germany February 5, 1920.

One of the chief requirements for the proper working of a metal vapor rectifier is a good cooling. nicates with the main space between the plates *a* and *f*.

By the use merely of the ordinary cooling jacket around the vacuum chamber of the rectifier it is not possible to convey the heat away from the difficultly accessible parts situated in the interior of the rectifier.

In metal vapor rectifiers for large outputs, 10 the anodes are provided each with a cooler for the purpose of conveying away effectively the heat generated at the anodes. It is thus obvious that the construction of a rectifier which comprises say six, anodes, and 15 where each anode is furnished with a cooler, will be complicated and very costly.

The present invention not only allows of dispensing with the connection of a cooler to each anode, but also it provides a means 20 of conveying away the heat from the difficultly accessible places in the interior of the working chamber.

According to this invention the construction is so arranged that a cooling medium, 25 such as air, water, etc., is caused to flow directly over portions of the walls of the casing or shields in which the anodes are located, and thereby the areas about the anodes subjected to cooling influence.

30 This may be effected for instance as illustrated in the embodiment illustrated in Fig. 1 of the accompanying drawings in which there is provided a common supporting plate *a* for supporting anodes *a''* and enveloping shields *b* for the anodes, the plate *a* being spaced from the vacuum chamber *c* of the rectifier while the anode shields *b* project in an air tight manner into the vacuum chamber *c* being partially enveloped by the 35 space *d* between the cover *f* and the chamber *c* so that a cooling medium such as air or water may be passed through said space and in direct contact with the outer surface of said shield *b* over a part of its length. The 40 cooling space is enlarged by the provision of a second shield *e* suspended in an air tight manner from an opening in the cover *f* of the chamber *c* and sealed at its lower end to the outer surface of the first men- 45 tioned anode shield *b* by means of the annular sealing member *g*. In other words by the provision of the shield *e* a cylindrical cooling space is provided about the major portion of the anode shield *b* which commu-

nicates with the main space between the plates *a* and *f*. The cooling may also be effected in the manner illustrated in Fig. 2, so as to provide the largest possible free space *d'* between the anode-supporting plate *a'* and the cover-plate *f'* of the working chamber, so that in the said free space the cooling medium can flow over the shields *b'* of the anodes *a'''* and can convey away the heat conducted from the chamber *c'* by the shields.

What I claim is:—

1. An apparatus for cooling a metal vapor rectifier including in combination a supporting plate, a metallic vacuum chamber spaced therefrom, an anode extending through the supporting plate, a shield surrounding the anode and projecting from the supporting plate in an air tight manner into the vacuum chamber so that a cooling medium may be passed through the space between the plate and the chamber and in direct contact with the outer surface of said shield over part of its length. 70

2. An apparatus for cooling a metal vapor rectifier including in combination a supporting plate, a metallic vacuum chamber spaced therefrom, an anode arranged through the supporting plate, a shield surrounding the anode and projecting in an air tight manner 80 into the chamber, a second shield projecting in an air tight manner into the vacuum chamber and surrounding in spaced relation the first shield and connected in an air tight manner at the end projecting into the chamber to the adjacent end of the first shield forming a cooling chamber which coacts with the space between the supporting plate and the vacuum chamber so that a cooling medium 85 may be passed therethrough and about 90 the first shield. 95

3. In vapor rectifying apparatus, a casing, an electrode, a supporting member for said electrode disposed exteriorly of and spaced from a wall of said casing and providing 100 therewith a ventilating passage, and a heat-conductive shield disposed about said electrode and sealed with respect to and traversing the space between said member and said wall, one end of said shield being open with 105 respect to the interior of said casing to provide communication between the same and said electrode.

4. In vapor rectifying apparatus, a casing, an electrode, a supporting member for said electrode disposed exteriorally of and spaced from a wall of said casing and providing therewith a ventilating passage, a heat-conductive shield disposed about said electrode and sealed with respect to and traversing the space between said member and said wall, one end of said shield being open with respect to the interior of said casing to provide communication between the same and said electrode, and means associated and cooperating with said shield to provide a cooling passage adjacent to and exterior of the latter and communicating with said first-named passage and being closed with respect to the interior of said casing.
5. In vapor rectifying apparatus, a vertically disposed casing having a substantially flat cover plate provided with circumferentially arranged openings, electrodes associated with said casing at said openings, a substantially flat supporting plate common to said electrodes disposed above and in spaced substantially parallel relation with respect to said cover plate to provide therewith a ventilating passage, and heat-conductive shield means disposed about said electrodes and extending downwardly through said openings into said casing and being sealed with respect to said plates, the portions of said shield means interior of said casing being open with respect to the latter to provide communication between the same and said electrodes, and means providing said interior portions with cooling passages communicating by way of said openings with said first-named passage and being closed with respect to the interior of said casing.
6. In vapor rectifying apparatus, a vertically disposed casing having a substantially flat cover plate provided with circumferentially arranged openings, electrodes associated with said casing at said openings, a substantially flat supporting plate common to said electrodes disposed above and in spaced substantially parallel relation with respect to said cover plate to provide therewith a ventilating passage, heat-conductive shield means disposed about said electrodes and extending downwardly through said openings into said casing and being sealed with respect to said plates, the portions of said shield means interior of said casing being open with respect to the latter to provide communication between the same and said electrodes, and means providing said interior portions with cooling passages communicating by way of said openings with said first-named passage and being closed with respect to the interior of said casing.

In testimony whereof I have signed my name to this specification.

JOHANN BROGER.
